UNITED STATES PATENT OFFICE

HENRY J. WAGNER, OF LA SALLE, ILLINOIS, ASSIGNOR TO WESTERN CLOCK COMPANY,
OF PERU, ILLINOIS, A CORPORATION OF ILLINOIS

DESIGN FOR A WATCH DIAL OR SIMILAR ARTICLE

Application filed April 25, 1932. Serial No. 43,800. Term of patent 3½ years.

To all whom it may concern:

Be it known that I, HENRY J. WAGNER, a citizen of the United States, residing in the city of La Salle, in the county of La Salle and State of Illinois, U. S. A., have invented a new, original, and ornamental Design for a

Watch Dial or Similar Article, of which the following is a specification, reference being had to the accompanying drawing, forming a part thereof.

In the drawing:

The figure is a front view of a dial showing my new design. While the drawing is executed in black lines and effects it will be understood, of course, that said design can be used made up in various colors and color schemes.

I claim:

The ornamental design for a watch dial or similar article, as shown and described.

HENRY J. WAGNER.
